BUMPER CLAMP

Filed July 14, 1927

UNITED STATES PATENT OFFICE.

HERBERT S. JANDUS, OF DETROIT, MICHIGAN, ASSIGNOR TO THE C. G. SPRING & BUMPER COMPANY, OF DETROIT, MICHIGAN, A CORPORATION OF DELAWARE.

BUMPER CLAMP.

Application filed July 14, 1927. Serial No. 205,589.

This invention relates to a clamp for a vehicle bumper. It is an object of the invention to hold the several bars of the bumper in such a manner that they will be rigidly secured to each other and so avoid rattling. It is a further object to provide a clamp which will hold an ornamental plate in its proper position relative to the bars of the bumper. It is another object to produce a clamp that will perform the above mentioned functions and which will at the same time present a pleasing ornamental appearance in connection with the rest of the bumper. Further objects will be apparent from the following description and from the use of the articles covered by the claims.

In the drawings Fig. 1 represents a plan view of a bumper using my clamp as a center clamp; Fig. 2 shows a fractional view of the central portion of the bumper shown in Fig. 1, showing the clamp in detail; Fig. 3 shows a sectional view taken on the line 3—3 of Fig. 2; Fig. 4 shows a plan view of the upper front clamp plate shown in Fig. 2.

In describing my invention I will assume the bumper to which it is applied to be connected to the front of a vehicle and the terms "front" and "rear" will be used in reference to this assumption. Of the reference characters shown in the several figures of the drawings 1 and 2 denote the impact bars of a bumper, which may be of the general type shown in the McGregor Patent 1,372,154 issued March 22, 1921, having a back bar 3 connected at its ends to the ends of the impact bars by means of pins 4, 4 and projecting forwardly at its central portion for connection to the central portion of the impact bars by means of the center clamp to be more fully described hereinafter.

The numeral 5 denotes an ornamental plate, which may be of grooved steel and suitably shaped to give the desired attractive appearance, adapted to bear upon the front surface of the rear bar 3. The center clamp consists of a front plate 6, a front plate 7 and a rear plate 10, all held in position by means of bolts 8 and 9 passing through apertures in the plates 6, 7 and 10.

The front plate 6 has a semi-cylindrical lug 11 projecting from its rear surface and adapted to fit into a suitably shaped aperture 12 in the upper edge of the ornamental plate 5. The plate 6 also has two lugs 13 and 14, which

are herein shown as L-shaped, projecting from the rear surface thereof, and which are adapted to pass between the bars and bear at their upper and lower surfaces upon the lower and upper edges of the bars 1 and 3 respectively. The lower portions 15 and 16 of the lugs 13 and 14, respectively, extend rearwardly beyond the rear bar 3 to give an extended bearing thereon and to provide stops to prevent the side motion of the rear clamp plate 10. The plate 6 is adapted to bear at its upper rear surface upon the front surface of the bar 1 and at its lower rear surface upon the front surface of the plate 5. The back plate 10 is bent forwardly at its end portions and so adapted to bear at its central portion upon the rear surface of the rear bar 3 and at its end portions upon the rear surfaces of the impact bars 1 and 2.

The front plate 7 is of identical construction with that of plate 6 and similar parts thereof have been denoted by reference characters which are the same as those shown on the plate 6.

In assembling my center clamp the plate 5 is suitably positioned on the bar 3 and the front plates 6 and 7 are placed so that the lugs 13 and 14 pass between the edges of the impact bars 1 and 2 and of the rear bar 3, and so that the lugs 11, 11 coincide with apertures 12, 12 at the upper and lower edges of the plate 5. The bolts 8 and 9 are passed through the apertures 17, 17 in the front plates 6 and 7 and through apertures in the rear plate 10, which latter plate is positioned between the extended lugs 15 and 16 so as to bear upon the rear surfaces of the impact and rear bars. By tightening the nuts 18 and 19 the plate 5 is held firmly in position against the rear bar 3, and the impact and rear bars are held rigidly in the proper spaced relation. The lugs 15 and 16 prevent side movement of the rear plate 10, the lugs 13 and 14 prevent upward and downward movement of the plates 6 and 7 or of the bars 1, 2 and 3, and the lugs 11 in the apertures 12 prevent side motion of the plate 5.

The spaced lugs 13 and 14 furnish spaced bearing surfaces between the edges of the bars and provide a space for the reception of the rear clamp plate together with a space for the stems of the bolts 8 and 9 connecting the front and rear clamp plates.

It is apparent that the clamp described

above can be used on bumpers differing from that herein shown and described, and further, that it may be used at other points on the bumper where it is desired to hold several bars in proper spaced relation. It is also apparent that a one-piece plate could be substituted for the two plates 6 and 7 without going beyond the scope of my invention and it is not intended to limit the scope of my invention to the two piece clamp shown. The clamp has been shown connecting three bars of a bumper but it is apparent that it could be used to clamp two bars of the bumper and in so doing one of the plates could be omitted.

Having thus described my invention, what I claim is:—

1. A clamp for holding vehicle bumper bars in proper spaced relation, said clamp including a plurality of plates adapted to bear upon the front surfaces of bars of the bumper, each plate having spaced lugs projecting from the rear surface thereof and adapted to fit between the spaced bars and bear upon the adjacent edges thereof, a plate adapted to bear upon the rear surfaces of said bars and means for drawing the plates toward each other.

2. A clamp for holding vehicle bumper bars in proper spaced relation, said clamp including a plurality of plates adapted to bear upon front surfaces of bars of the bumper, each plate having spaced lugs projecting from the rear surface thereof and adapted to fit between and project beyond the rear surfaces of the bars and to bear upon adjacent edges thereof, a plate adapted to fit between the portions of the lugs projecting beyond the bars and to bear upon rear surfaces of the said bars, and means for drawing said plates toward each other.

3. The combination with a pair of bumper bars and a plate adapted to bear upon and be clamped to one of said bars, of means for clamping said plate and bars in proper spaced relation, said means including a front clamp plate adapted to bear upon the front surface of one of the bars and upon the front surface of the clamped plate, means connected to said clamp plate for preventing side motion of the clamped plate, a rear clamp plate adapted to bear upon the rear surfaces of said bars and means for drawing the said clamp plates toward each other.

4. The combination with a pair of spaced bumper bars and a plate adapted to bear upon and be clamped to one of said bars, of a front clamp plate adapted to bear upon a surface of the clamped plate and a surface of a bar, said clamp plate having a lug adapted to fit into an aperture in said clamped plate, a rear clamp plate adapted to bear upon the opposite surface of the bars and means for drawing said clamp plates toward each other.

5. The combination with a pair of spaced bumper bars and a plate adapted to bear upon and be clamped to one of said bars, of a front clamp plate adapted to bear upon a surface of a bar and upon a surface of said clamped plate, said clamp plate having lugs projecting therefrom which are adapted to pass between the spaced bumper bars, means for preventing side motion of the clamped plate, a plate adapted to bear upon the rear surfaces of the bars, and means for drawing said clamp plates toward each other.

6. The combination with a pair of spaced bumper bars and a plate adapted to bear upon and be clamped to one of said bars, of a front clamp plate adapted to bear upon a surface of a bar and upon a surface of said clamped plate, said clamp plate having lugs projecting therefrom which are adapted to pass between the spaced bars and bear upon the edges thereof, and means for preventing side motion of the clamped plate, said means consisting of a lug projecting from the clamp plate and adapted to fit into an aperture in the clamped plate, a rear clamp plate adapted to bear upon the rear surfaces of the bars and means for drawing said clamp plates toward each other.

7. The combination with a pair of spaced bumper bars and a plate adapted to bear upon and be clamped to one of said bars, of a front clamp plate adapted to bear upon a surface of a bar and upon a surface of said clamped plate, said clamp plate having spaced lugs projecting therefrom which are adapted to pass between the spaced bars and bear upon the edges of the same, and means for preventing side motion of the clamped plate, a rear clamp plate adapted to bear upon the rear surfaces of the bars and means for drawing said clamp plates together.

8. The combination with a pair of spaced bars and a plate adapted to bear upon and be clamped to one of said bars, of a clamp plate adapted to bear upon a surface of a bar and upon a surface of said clamped plate, said clamp plate having spaced lugs projecting therefrom between the spaced bars and beyond the rear surfaces thereof, means for preventing side motion of the clamped plate, a rear clamp plate adapted to fit between the lugs projecting from the front plate and to bear upon the rear surfaces of the bars, and means for drawing the said clamp plates toward each other.

9. The combination with three spaced bumper bars and a plate adapted to bear upon and be clamped to one of said bars, of a pair of front clamp plates each adapted to bear upon the front surface of a bar and upon the front surface of the clamped plate, lugs projecting from the rear surfaces of the front plates which are adapted to pass between the spaced bars and bear upon the edges thereof, a rear plate adapted to bear upon the rear

surfaces of the spaced bars, and means for drawing the front and rear clamp plates toward each other.

10. The combination with three spaced bumper bars and a plate adapted to bear upon and be clamped to one of said bars, of a pair of clamp plates each adapted to bear upon a surface of a bar and upon a surface of the clamped plate, said clamp plates each having a pair of spaced lugs projecting between the spaced bars and beyond the rear surfaces thereof, means for preventing side motion of the clamped plate, said means consisting of a lug attached to a front clamp plate and adapted to fit into an aperture in the said clamped plate, a rear clamp plate adapted to fit between the first mention projecting lugs of the front clamp plates and to bear upon the rear surfaces of the bars, and means for drawing said clamp plates toward each other.

11. The combination with a pair of impact bars, a rear bar and a plate adapted to be clamped to said rear bar, of a clamp consisting of a pair of front clamp plates each adapted to bear upon the front surface of an impact bar and upon the front surface of the clamped plate and each having lugs projecting from the rear surface thereof and adapted to extend between and bear upon the edge of an impact bar and that of a rear bar, means for preventing side motion of the said

clamped plate, a rear clamp plate adapted to bear upon the rear surfaces of the impact and rear bars and means for drawing said front and rear clamp plates toward each other. 35

12. The combination with a plate adapted to bear upon and be clamped to a bar, of means for holding said plate and bar in contact with each other, said means including front plates adapted to bear upon the front surface of said first mentioned plate, said front plates having lugs adapted to fit within notches in the edges of the first mentioned plate, a rear plate adapted to bear upon the rear surface of the said bar, and means for drawing said front and rear plates toward each other. 40 45

13. The combination with a pair of spaced impact bars, a rear bar arched forwardly for connection to said impact bars, and a plate adapted to be clamped to said rear bar, of a pair of front plates each having a lug adapted to fit within an aperture in said clamp plate 50 and spaced lugs adapted to extend between and bear upon the adjacent edges of the front and rear bars, a rear plate adapted to bear upon the rear surface of the rear bar, and means passing between said spaced lugs for 55 drawing said front and rear plates together. 60

In testimony whereof, I hereunto affix my signature.

HERBERT S. JANDUS.
